his ATTORNEY

UNITED STATES PATENT OFFICE.

FRANCIS A. BARR, OF HESTER, MISSOURI.

HAND CORN-PLANTER.

SPECIFICATION forming part of Letters Patent No. 236,293, dated January 4, 1881.

Application filed September 29, 1880. (Model.)

To all whom it may concern:

Be it known that I, FRANCIS A. BARR, of Hester, in the county of Marion and State of Missouri, have invented a new and valuable 5 Improvement in Hand Corn-Planters; and I do hereby declare that the following is a full, clear, and exact description of the construction and operation of the same, reference being had to the annexed drawings, making a part of 10 this specification, and to the letters and figures of reference marked thereon.

Figure 1 of the drawings is a representation of a plan view. Fig. 2 is a central vertical section.

15 This invention relates to devices for dropping corn by hand; and it is intended as an improvement on a patent granted to me October 24, 1876, No. 183,624, the present improvement being in the construction of the 20 dropper.

The invention consists in a dropper of peculiar construction, whereby corn of different sizes may be planted, and also choking easily prevented.

25 In the annexed drawings, A represents a portion of one of the legs of a hand corn-planter, to which the dropper B is attached.

C represents the bottom of a hopper which receives the corn. This hopper is made fast 30 to the leg A, and below is attached, to the same leg, the chute D, ending in opening d'. The upper opening, d, of this chute is immediately below a sector-opening, e, of the hopper C.

35 Extending to one side of chute D is the flange E, having the stud e. Between said flange E and hopper C is a plate, F, whose recess f fits stud e, upon which said plate F revolves. This plate F has three recesses or 40 pockets, g g' g'', of different sizes, to suit varying sizes of corn. On the periphery of plate F there are three flanges, h, having holes h'.

To one end of opening e there is attached to hopper C a hinged flap, H, which is arranged 45 with its body on a plane with the bottom of the hopper, so that it in fact forms a portion of said bottom. By arranging it as a portion of the said bottom it fits closely above the plate F and acts to sweep off seed from the 50 pockets, leaving the proper amount, and yet, by the construction afterward to be described, it readily yields to a choke. A pin, I, passing through ears i i, standard k, and the rim of the hopper, holds the flap to said hopper, and a 55 spring, K, holds the flap flat. This flap H is

hinged at its rear edge upon pin I, without any extension beyond said pin, and the spring K, surrounding said pin, bears with one end upon said flap and with the other upon the bottom of the hopper. By this construction, if any 60 choking occurs at the seed-opening, the flap will be forced up, which will relieve such choke and allow the accumulated seed to fall through the opening, and as the plate F is turned back the flap H falls. By pivoting the flap at its 65 rear edge it can be pushed any distance, even beyond a vertical position; so no matter how bad the choke it will be relieved.

When it is desired to use the device a rod is placed in one of the holes h', the proper one 70 being determined by the size of corn to be planted. The other end of the rod is fastened to the other leg of the device (not shown) and the plate F is operated like the slide in my patent referred to. As the pocket or recess 75 comes to that portion of the opening e in hopper C, between edge e' and the flap H, it fills with corn, the flange E preventing it from dropping out. As the plate moves on, the corn slides along until it reaches opening d of chute 80 D, when it slides down said chute, as described in my patent referred to. As the plate F is moved and the pocket approaches flap H, the edge of the latter clears the grain from above the pocket, and only that in said pocket reaches 85 the opening of the chute; but if the corn should become choked the pressure would overcome the resistance of spring K and throw the flap back; but the corn thus choked would fall, with that in the pocket, through chute D, and 90 the flap H would then fall back and resume its normal function.

By hinging the flap instead of making it slide, it can be readily acted upon by the choked corn pushing upward, and has no need 95 of a special device to move it.

What I claim is—

The flap H, hinged to the hopper and held by a spring, as described, and having its body in the plane of the bottom of the hopper, and 100 forming a portion of the same, substantially as and for the purpose described.

In testimony that I claim the above I have hereunto subscribed my name in the presence of two witnesses.

FRANCIS ANDERSON BARR.
